STAND FOR SUPPORTING A ROCK SPECIMEN

Jack E. Blake, 514 Gulf Bldg., Midland, Tex. 79701

Filed Oct. 11, 1974, Ser. No. 514,188

Term of patent 7 years

Int. Cl. D6—99

U.S. Cl. D6—85

Fig. 1

Fig. 2

Fig. 3

FIG. 1 is a plan view of the stand for supporting a rock specimen showing my new design;

FIG. 2 is a side elevational view thereof; and

FIG. 3 is a side elevational view thereof taken from the opposite direction of FIG. 2.

I claim:

The ornamental design for a stand for supporting a rock specimen, substantially as shown.
